UNITED STATES PATENT OFFICE.

JESSE M. GARBER, OF INDIANAPOLIS, INDIANA, ASSIGNOR TO NORDYKE & MARMON COMPANY, OF INDIANAPOLIS, INDIANA, A CORPORATION OF INDIANA.

SHAFT-BEARING.

1,096,298.

Specification of Letters Patent. Patented May 12, 1914.

Application filed March 20, 1911. Serial No. 615,805.

To all whom it may concern:

Be it known that I, JESSE M. GARBER, a citizen of the United States, residing at Indianapolis, in the county of Marion and 5 State of Indiana, have invented a new and useful Shaft-Bearing, of which the following is a specification.

The object of my invention is to produce an automatically lubricating journal bearing.

The accompanying drawings illustrate my invention.

Figure 1 is an axial section of the bearing structure complete; Fig. 2 a plan of the 15 lower section; Fig. 3 a section on line 3—3 of Fig. 1; Fig. 4 a section on line 4—4 of Fig. 1; Fig. 5 a perspective detail of the oil deflector, and Fig. 6 a fragmentary detail of the means for closing one end of the 20 structure.

In the drawings, 10 and 11 indicate two mating bearing members or bodies. The member 10 is provided with a semi-cylindrical seat 12 beneath which is formed an 25 oil reservoir 13. At each end, the body 10 is provided with a semi-annual groove 14 which perforates the seat 12 so as to give access to the oil chamber 13 and, at the middle of the body the seat 12 is perforated by 30 a slot 15 which also gives access to the oil chamber 13. Mounted in each end of the seat 12 is a semi-annual bearing bushing 16 which, at its inner end, is formed with a flange 17 which holds it against axial 35 placement in one direction. The two bearing bushings 16 are alined and are adapted to receive properly formed portions of shaft 18. Secured to shaft 18 is a circumferential 40 rib or flange 19 which lies between the separated adjacent ends of the bushings 16 and is of sufficient diameter to project well 45 into the oil chamber 13. Each bushing 16 at one edge is cut away, as indicated at 21, opposite a wick seat 22 formed in body 10 and extending longitudinally of the seat 12. The wick seat 22, at each of its ends, 50 communicates with a vertical passage 23 which extends down through the body of the member 10 and communicates with the oil reservoir 13. Mounted in each wick seat 22 is a 55 wick 24 the ends of said wick being carried down through the passages 23 and projected well into the oil reservoir 13, as clearly indicated, the wick having sufficient diameter to rub against the shaft 18.

The member 11 is provided with a semi-cylindrical seat 31 which mates with seat 12 and the middle of said seat is provided with a semi-annual groove or recess 15' which mates with the groove 15 of member 10. 60 Mounted in the ends of seat 31 are semi-annual bearing bushings 16' which mate with the bushings 16 and are similarly provided with inner flanges 17'. Formed through the upper side of member 11 and 65 extending for a considerable portion of the axial length of said member, is a slot or inspection opening 32 which may be covered by a readily removable cover 33. Formed through each bushing 16', at its upper side 70 immediately beneath the opening 32, is a slot 34 which extends through flange 17' and, at its end farthest from the flange is widened, as indicated in Fig. 1, so as to expose shaft 18 immediately beneath the opening 32. Formed loosely within the opening 32 is an oil-deflecting saddle 35 which, at one side, is provided with a depending flange 36 having a middle notch 37 which is formed to fit freely but closely over the flange 19 80 of shaft 18. The upper or main plate of the saddle 35 is substantially horizontal and, at its edge first passed by points on the shaft, is provided with a pair of depending, diverging deflecting wings 38, 38 flanking 85 the flange 19. At its outer ends the saddle 35 is provided with depending guard ends 39, 39 and, at the lower corner of the junction of each of these ends with the flanges 36, the parts are cut out to form a notch or oil 90 passage 41. If shaft 18 is not to extend entirely through the bearing structure above described, a circular plate 42 may be provided, as illustrated in Fig. 6, to close one end of the structure. 95

The operation is as follows: Rotation of shaft 19 in the direction indicated by the arrow in Fig. 3 carries the oil in chamber 13 up upon flange 19 and, when the oil reaches flange 36 of the saddle 35, said flange scrapes 100 the surplus from flange 19. The oil strikes the flange 36 with considerable force and tends to bank up into the corner between the upper plate of the saddle and the flange 36. The divergent wings 38, which stop short of the ends 39, guide this oil through the passages 41 into the opening 32 and slots 34, which form the sides of an oil reservoir of considerable size, the bottom of which reservoir is formed by the shaft itself. From 110

this reservoir, the oil passes down with the shaft between the shaft and the bearing bushing 16'. Surplus of oil, when it reaches the wick seat 22, will flow axially of the 5 shaft and down through the groove 14 into the oil reservoir. If on the other hand, the oil within the reservoir should fall below flange 19, the wicks 23 will serve to draw the oil upwardly and deliver the same to the 10 shaft. The flange or oil guard 45 on the shaft opposite the groove 14 at the end of the journal bearing from which the shaft projects, prevents the oil from creeping along the shaft, by throwing it by centrifugal force through such groove back into the oil chamber 13.

I claim as my invention:

1. A bearing structure comprising a pair of mating members forming a shaft seat 20 therebetween, the lower member having an oil reservoir formed therein with an intermediate communication between the shaft seat and the oil reservoir and the upper member having a longitudinal pocket communicating with the shaft seat; a shaft mounted in the shaft seat and carrying a circumferential flange projecting into the oil reservoir and the pocket, and an oil-deflecting saddle mounted in the pocket of the 25 upper member and closely straddling the shaft flange in such manner as to receive oil therefrom, said saddle comprising a portion overlying the shaft flange and provided with depending oil deflectors and with a 30 flange depending toward the shaft for removing oil from the flange on the shaft after such oil has been carried by the rotation of the shaft past such oil deflectors,

such depending flange being separated from the oil deflectors in the direction of rotation 40 of the shaft.

2. A bearing structure comprising a lower member having a pair of axially separated bushing seats and an oil reservoir communicating with the space between said bushing 45 seats, a pair of axially separated bushings mounted in said bushing seats, a mating upper member having a pair of axially separated bushing seats and an oil pocket formed in its upper side, a pair of 50 axially separated bushings mounted in said last mentioned bushing seats and each having an opening through its upper side opposite the oil pocket, a shaft journaled in said bushings and carrying a circumferential 55 flange lying between the axially separated bushings of both pairs and extending into the oil reservoir and the oil pocket, and an oil-deflecting saddle loosely mounted within the oil pocket and comprising a portion 60 which overlies the shaft flange and is provided with a depending notched flange closely straddling the shaft flange and with depending oil-deflecting flanges, said oil deflecting flanges being spaced from said 65 notched flange in a direction opposite to the direction of rotation of the shaft.

In witness whereof, I have hereunto set my hand and seal at Indianapolis, Indiana, this 17th day of March, A. D. one thousand 70 nine hundred and eleven.

JESSE M. GARBER. [L. S.]
